[57] CLAIM

The ornamental design for a protector for a roll of tape, as shown and described.

DESCRIPTION

FIG. 1 is a perspective view of my new design;

FIG. 2 is a front view thereof;

FIG. 3 is a rear view;

FIG. 4 is a right side view thereof;

FIG. 5 is a top view thereof, the bottom view being a mirror image thereof; and,

FIG. 6 is a left side view thereof.

Broken lines are included in the drawing to show a part of the roll of tape for illustrative purposes only. The broken lines form no part of the illustrated design.
